UNITED STATES PATENT OFFICE.

JOHN A. HUNTER, OF PHILADELPHIA, PENNSYLVANIA.

METALLURGICAL FURNACE.

SPECIFICATION forming part of Letters Patent No. 699,759, dated May 13, 1902.

Application filed August 9, 1900. Renewed October 10, 1901. Serial No. 78,242. (No model.)

To all whom it may concern:

Be it known that I, JOHN A. HUNTER, a citizen of the United States, residing in Philadelphia, Pennsylvania, have invented certain 5 Improvements in Metallurgical Furnaces, of which the following is a specification.

My invention relates particularly to metallurgical furnaces intended for the treatment of solid forms of cast-iron for the purpose of 10 converting the same into steel, one object of my invention being to so construct the furnace that it can be readily used either as an open-hearth furnace for the purpose of heating the articles under treatment to the desired 15 temperature or as a closed or muffle furnace during the time that such articles are being subjected to the converting treatment.

A further object of the invention is to provide efficient means for introducing and distributing 20 throughout the working chamber of the furnace the agent used for the conversion of the iron.

In the accompanying drawings, Figure 1 represents a longitudinal section of a furnace 25 constructed in accordance with my invention. Fig. 2 is a transverse section of the same on the line *a a*, Fig. 1. Fig. 3 is a transverse section on the line *b b*, Fig. 1; and Fig. 4 is a perspective view, on a larger scale, of a block 30 such as is used in the bottom or floor of the working chamber of the furnace.

In Figs. 1 and 2 the working chamber of the furnace is shown at 1, said furnace having at the rear a flue 2 and at the top a flue 3, 35 communicating with the flue 2 and with the stack 4. The working chamber of the furnace communicates with the rear flue 2 through an opening 5, provided with sliding dampers 6 or other appropriate means where- 40 by communication between the working chamber and the flue 2 through the opening 5 may be permitted or obstructed, as desired, and the flue 2 communicates at its lower end with flues 7 beneath the working chamber of 45 the furnace.

A series of gas or oil burners 8 discharges into the working chamber 1 through openings in the front wall of the furnace, and a similar burner 9 discharges into the front end 50 of each of the bottom flues 7. The body or floor of the working chamber 1 of the furnace is composed of blocks or slabs 10, each hav-

ing in the upper surface a recess 11, so as to leave projecting ribs 12, upon which the articles to be treated are supported. In each 55 block 10, below the recessed portion of the same, is also formed a longitudinal opening or channel 13, which communicates with the recess 11 of the block through a series of passages 14, preferably flared outwardly toward 60 the top and discharging into the recess, and with these channels communicate nozzles 15, projecting from pipes 16, through which the treating agent is forced or permitted to flow.

A bridge-wall 20 serves to break up and dis- 65 tribute the flames from the burners 8, so as to cause equal heating of all portions of the charge in the chamber 1.

In operating the furnace the working chamber 1 is first charged with the articles to be 70 treated, and the dampers 6 are opened, so as to provide for a free communication between said working chamber and the rear flue 2. A heating-flame is then projected into the working chamber from the burners 8, and this 75 flame is continued until the articles in the working chamber have been raised to the desired temperature, the products of combustion escaping through the opening 5, rear flue 2, and top flue 3, so as to heat the top 80 arch or crown of the furnace and prevent any loss of heat by radiation therefrom. When the articles in the working chamber have been heated to the desired temperature, the flame from the burners 8 is cut off, the dampers 6 are closed, and flame from the burners 9 is projected into the flues 7 beneath 85 the floor of the working chamber. This flame, after traversing the flues 7, rises through the rear flue 2 and passes again to the front over 90 the top of the furnace through the flue 3, so as to maintain the furnace in a highly-heated condition and prevent rapid loss of heat by the contents of the working chamber. At the same time the treating agent, which may be 95 the gas arising from mixtures such as those described in my Patent No. 600,948, dated March 22, 1898, is forced or permitted to flow into the channels 13 of the blocks 10, constituting the floor of the working chamber, and passes from these channels through the passages 14 into the recesses 11 of the blocks 100 and thence rises into the working chamber, so as to come into contact with all parts of

the heated charge contained therein, the flow of the treating agent being continued until the desired conversion of the iron is effected.

If it becomes necessary to reheat the iron 5 during the treatment, the flow of the treating agent can be cut off and the heating-flame again projected into the chamber from the burners 8, the dampers 6 being opened and the flame in the bottom flues 7 being continued or discontinued, as desired. When 10 the reheating of the iron has been effected, the flame from the burners 8 may be cut off, the dampers 6 again closed, and the flow of the treating agent into the furnace resumed. 15 By this means I am enabled to quickly change the furnace from an open-hearth into a closed or muffle furnace and I am enabled to effect the distribution of the treating agent throughout all portions of the working chamber, so 20 that all of the articles contained therein will be uniformly acted upon by said treating agent.

When the blocks 10, constituting the floor of the working chamber, are long enough to 25 extend completely across the furnace, the partitions separating the flues 7 in the bottom of the furnace will be unnecessary, and a single flue can be used in place of the double flue, and a single burner 8 or 9 may replace the series of burners in furnaces of 30 small size.

When the treating agent is generated in the working chamber of the furnace or is introduced thereto at some other point than the 35 bottom, said bottom portion of the furnace may simply be provided with ribs, of refractory material, for raising the mass of material to be treated and insuring the access of the treating agent to the under side of said 40 mass.

The return-flue 3 in the top of the furnace serves to economize the heat by preventing radiation from the top arch or crown of the working chamber, and the use of this flue is 45 therefore always to be preferred, although it is not absolutely necessary to the broader embodiment of my invention, which contemplates the use of a rear chimney or stack communicating directly with the rear flue 2, if 50 desired.

The furnace may also be constructed with a fireplace intended for use of coal, such fireplace communicating through dampered openings with the front end of the working 55 chamber and with the front end of the flue or flues 7, so that the products of combustion can be directed to either working chamber or flues, as desired.

Having thus described my invention, I

claim and desire to secure by Letters Pat- 60 ent—

1. A metallurgical furnace having a working chamber, a flue beneath the floor of the same, a discharge-flue communicating with said base-flue, and a dampered opening at 65 that end of the working chamber, through which said working chamber communicates with the discharge-flue, and means for supplying heat independently to the working chamber and the base-flue, substantially as 70 specified.

2. A metallurgical furnace having a working chamber, a flue beneath the floor of the same, a rear flue communicating with said base-flue, and a dampered opening at that end 75 of the working chamber, through which said working chamber communicates with the rear flue, a return-flue over the top arch or crown of the working chamber, and means for supplying heat independently to the working 80 chamber and base-flue, substantially as specified.

3. A metallurgical furnace having a working chamber with bottom provided with ribs or projections for the support of the material 85 to be treated, means for heating said material by gaseous products of combustion introduced into the working chamber, and provision for introducing a fluid treating agent into said working chamber, independently of the 90 gaseous products of combustion, substantially as specified.

4. A metallurgical furnace having a working chamber, combined with means for introducing gaseous products of combustion into 95 the same and a floor composed of blocks having therein channels or passages for conveying a fluid treating agent into the furnace independently of the gaseous products of combustion, substantially as specified. 100

5. A metallurgical furnace combined with means for introducing gaseous products of combustion into the same and having a floor composed of blocks with recessed upper faces, and channels or passages communicating with 105 said recessed faces of the blocks and providing for the introduction of a fluid treating agent into the furnace, independently of the gaseous products of combustion, substantially as specified. 110

In testimony whereof I have signed my name to this specification in the presence of two subscribing witnesses.

JOHN A. HUNTER.
